UNITED STATES PATENT OFFICE.

ROBERT W. SCHWEIMLER AND PAUL A. POULALION, OF WHEELING, WEST VIRGINIA,
ASSIGNORS TO COMPO-TILE FIREPROOFING COMPANY, OF WHEELING, WEST VIR-
GINIA, A CORPORATION OF WEST VIRGINIA.

BUILDING CONSTRUCTION.

1,255,235.

Specification of Letters Patent.

Patented Feb. 5, 1918.

Application filed August 31, 1917. Serial No. 189,128.

To all whom it may concern:

Be it known that we, ROBERT W. SCHWEIMLER and PAUL A. POULALION, citizens of the United States, and residents of Wheeling, in the county of Ohio and State of West Virginia, have invented new and useful Improvements in Building Constructions, of which the following is a specification.

Our invention is an improvement in building construction, and has for its object to provide means in connection with floors and walls composed of concrete blocks, metal forms, gypsum blocks, hollow tiles or the like, for use as a guide or leveling point to assure a uniform thickness of floor, and as a support and nailing block for floor sleepers or the like.

In the drawings:

Figure 1 is a perspective view of one of the blocks;

Fig. 2 is a transverse vertical section of a complete floor;

Fig. 3 is a longitudinal section.

In the present embodiment of the invention, the improvement is shown in floor construction, the floor consisting of series of blocks which are laid in courses, as shown in Fig. 2.

The top of the block has at the center of the top a boss or block 3 extending upwardly, and of a depth which will bring the top of the boss to the level of the plastic portion of the floor indicated at 4. As shown in Fig. 2, the blocks are laid in courses, with the courses alongside each other, and the tops of the bosses 3 are at the same level, forming a guide for the

floor of plastic material 4, and insuring the level of the floor and absolute uniformity.

The sleepers 5 for the floor may be laid 40 directly upon the bosses 3 and nailed thereto, and the finished floor 6 is laid upon the sleepers in the usual manner.

The blocks may be tied together by reinforcing rods indicated at 7, which are laid 45 at opposite sides of the bosses 3, and are secured to the blocks by angle nails 8.

While the improved blocks are shown in floor construction, it is obvious that they might be used in wall or ceiling construction 50 with equal facility, the bosses forming a guide for the laying of the plaster. The bosses may be made integral with the block as shown, or may be made separate and connected thereto in any suitable or desirable 55 manner.

In wall and ceiling constructions, the blocks will be made of a composition which will require only a white finish coat of plaster, indicated at 9, on the under sides 60 of the blocks.

We claim:

In building construction, a series of composition blocks adapted to be laid in courses, and each having at approximately the center thereof a boss or lug adapted to form a leveling guide for a floor of plastic material capable of hardening and to act as a nailing block for sleepers or the like, the blocks being tied together transversely of the series 65 by tie rods arranged at opposite sides of the bosses and secured to the blocks.

ROBERT W. SCHWEIMLER.
PAUL A. POULALION.
